UNITED STATES PATENT OFFICE.

HARRY VISSERING, OF KENILWORTH, ILLINOIS, ASSIGNOR TO THE OKADEE COMPANY, OF CHICAGO, ILLINOIS, A CORPORATION OF ILLINOIS.

LOCOMOTIVE FRONT-END SUPPORT.

Application filed May 13, 1922. Serial No. 560,563.

This invention relates to closure supports and particularly to a support for the type of closure used in boilers of railway locomotives, and commonly termed the front end as it is the plate for forming the forward end of the boiler.

This closure plate for the front end of a boiler is large and extremely heavy and according to approved railway practice is secured to the boiler front end by a great number of stud bolts and nuts circumferentially arranged adjacent the outer edge of the front end plate. To make the joint between the boiler front and the front end plate absolutely tight, the nuts are turned down as closely as possible. When it is desired to remove the front end plate to reach the inside of the boiler shell, the nuts are all removed and the front end plate moved away from the boiler shell. To loosen this front end plate and move it away from the boiler shell is rendered extremely difficult as there will be a tendency for the front end plate to stick due to the rusting of the parts and of the action of the elements, aside from the factor of its great weight.

Still another difficulty encountered in the removal of this front end plate is that its weight is such that a crane and tackle or the like is found necessary to carry the weight of the plate as soon as it is moved away from its position of support by the boiler. This necessitates that the engine be moved to a spot where such crane and tackle are at hand.

Again, when an attachment in the form of a hinge structure has been used by me, it has been found necessary to provide for lineal as well as pivotal movement of the parts in order to permit a sliding movement of the front end on the stud bolts. This lineal movement of the parts of the hinge structure is objectionable inasmuch as there is not only a tendency to wear, but since two of such hinge structures are commonly, if not in fact, necessarily, employed by me, the possibility of such lineal movement involves the possibility, if not at times indeed the likelihood, of canting and consequent binding, owing to the tendency of the front end to swing downward about the lower hinge structure as an axis.

The principal objects of this invention, therefore, are to provide an improved arrangement whereby the front end plate can be moved away from the boiler front with-

out the expenditure of the amount of time and effort now required; the provision of an improved mounting between the front end plate and boiler front now in use generally which will permit the employment of the pivoted connection between such front end plate and boiler front; the provision of an improved construction by which the end closure plate may be moved laterally away from the boiler front without at the same time moving it bodily forward; the provision of an improved construction whereby the end closure plate can be moved away from the boiler front without at the same time moving it away from its position of support by the boiler; the provision of a novel arrangement which permits the front end plate to be swung to the side of the boiler front so as to permit free access to the boiler interior without at the same time withdrawing the end plate from its position of support by the boiler; the provision of improved means whereby the end closure plate may be secured to the boiler front by an approved arrangement of stud bolts and nuts circumferentially arranged adjacent to the outer edge of the front end plate, characterized by the fact that such removal may be readily accomplished, and further characterized by the fact that the end plate may be swung laterally to permit access to the boiler without straining such supporting means; together with such further and additional objects as may hereinafter be pointed out or appear as this description proceeds.

In attaining the objects referred to, and in gaining certain additional benefits and advantages to be below disclosed, I have provided certain constructions embodying my present invention, which are illustrated in the accompanying drawings, wherein Figure 1 is a front elevational view of a locomotive front and embodying one exemplification of my present improvements, the closure being shown in closed position.

Figure 2 is a sectional plan view of a portion of the structure of Figure 1, taken on the line 2-2 of such Figure and;

Figure 3 is a fragmentary sectional view, illustrative of a modified form of construction having my present improvements incorporated therein.

In the drawing, the boiler shell 10 and the front end closure plate 11 are held rigidly and tightly together in service condition by

means of a circular row of bolts and nuts 12.

As these parts are all exposed to the elements, the front end plate will tend to stick to the stud bolts and to the boiler front, and it is extremely difficult to pry the front end plate loose from the boiler front and handle it without elaborate tackle. Furthermore, when it is pried loose special provision must be made to support the weight of the front end plate and to move it away from the boiler opening so as to be able to reach the boiler interior.

With this in view, I have devised certain novel features of construction now to be described.

Rigidly fixed to the outer surface of the boiler 10, and closely adjacent to its front end I provide at spaced apart points the two bracket supports 13—13. Each of these brackets is provided with upper and lower spaced ears, 14—14, extending laterally from the boiler front for a substantial distance, each being provided with aligned openings 15 in vertical registration.

Passing through these openings 15 are the pivot pins 16, each supported from the upper ear 14 by its head 17, and retained in position against accidental loss by the cotter pin 18. To brace these ears 14 against distortion each bracket support 13 is provided with a rib member 19.

The front end plate 11 is mounted to swing about the pivot pin 16 as a hinge by means of the hinge members 20—20 extending laterally beyond the front end plate 11 and rigidly supported therefrom by means of the bracket members 21—21, each bracket member 21 being provided with two of the hinge members 20. These members 20 encircle the pin 16 so as to permit swinging movement between the members 20 and 14, limited to pivotal movement by means of the pin 16.

It will be observed that by virtue of the lateral displacement of the hinge members 45 to the side of the boiler structure the axis of the pivot pin 16 is relatively widely separated from the plane in which lies the nearest of the circular row of stud bolts and nuts 12.

In order to permit the swinging of the closure plate 11 about the axis of the pivot pin 16 without distortion of said bolts 12, I have given the openings in said closure plate 11 whereby said closure plate 11 is enabled to rest upon and be supported by said bolts 12 a horizontally elongated form, that is one having greater width than height. This not only permits bringing the front end closure member 11 to its predetermined relationship to the smoke box ring 23, since any lateral displacement is overcome by the limitation of lateral movement ensuing upon the functioning of the pins 16, but when the nuts 12^a are drawn up on the bolts 12 the plate 65 11 is supported by such bolts in desired rela-

tionship with the boiler and held in such supported position by the nuts 12^a.

For additionally supporting and guiding the pins 16, the bracket supports 13 are each further provided with ears 22 positioned intermediate to ears 14 and provided with vertical openings similar to and in registry with the openings 15 in the upper and lower ears 14.

As a result of the arrangement described, it will be apparent to those who are skilled in the art that I am enabled to provide by means of my improved attachments and changes that may be relatively easily made in existing structures, a construction which has all of the advantages of existing structures with the additional advantages due to the employment of such attachments, as hereinabove pointed out.

In Figure 3 of the drawing it will be observed that I have illustrated a modified form of the invention in which the smoke box ring 23^a is provided with a circumferential ring of horizontally elongated apertures 15^a whereby the bolts 12 are permitted to move horizontally, and thus in this modified form of the structure I am able to employ my attachments without change in the existing forms of front end closure plate 11 itself.

By virtue of the marked lateral extension of the members 13 and 20, I am enabled not only to lengthen the distance between the pivot pins 16 and the nearest of the stud bolts, 12, but also to so space away such pivot pins 16 as not to interfere with the line of vision of the engine men in sighting targets and other signals along the edge of the boiler, (which is an advantage of a value that will be wholly appreciated by those conversant with such matters,) but rather on the contrary to form a target sight.

Having thus described my invention and illustrated its use, what I claim as new and desire to secure by Letters Patent is:

In combination, a container having an opening, a plurality of stud bolts distributed substantially uniformly around said opening and fixed to said container, and a closure on said container for closing said opening and provided with a plurality of elongated apertures complementary to said bolts and of greater length than the diameter of said bolts, said apertures being parallel, and means for mounting said closure on said container including a hinge having its axis at right angles to the longer dimensions of said apertures and removed sufficiently beyond the axis of the nearest bolt so that the lateral component of movement of said closure relative to said bolts when swung out will be less than the length of said apertures.

In testimony whereof I have hereunto signed my name.

HARRY VISSERING.
